(57) CLAIM

The ornamental design for a windshield cover and protector, as shown and described.

DESCRIPTION

FIG. 1 is a front perspective view of a windshield cover and protector, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof, showing the windshield cover and protector in a using position.

The broken lines in the figures illustrate portions of the article that form no part of the claimed design. The broken lines showing of a car in FIG. 9 depict environmental structure that form no part of the claimed design.
